UNITED STATES PATENT OFFICE.

HENRY H. SIEVERT, OF CHICAGO, ILLINOIS.

DESIGN FOR A SEAT AND BACK FOR WATER-CLOSETS.

SPECIFICATION forming part of Design No. 21,438, dated March 29, 1892.

Application filed February 15, 1892. Serial No. 421,636. Term of patent 14 years.

To all whom it may concern:

Be it known that I, HENRY H. SIEVERT, a citizen of the United States, residing at Chicago, in the county of Cook and State of Illinois, 5 have invented and produced a new and original Design for Water-Closet Seats and Backs, of which the following is a specification, reference being had to the accompanying drawing, forming part thereof.

10 The figure in the drawing is a perspective view of a water-closet seat and back, showing my design.

15 The leading feature of my design consists in a series of smooth curved and smooth plane surfaces harmoniously arranged and disposed each in relation to the others, the several rounded or curved outlines being similar to each other and in part arranged one over or within another and in part one vanishing 20 into or continuing another to produce the single unitary effect or appearance of one tongue-like figure having a widened or spreading curved end projecting horizontally from an upright figure, the outline of which is 25 curved at each end correspondingly to the curved outline at the widened end of said horizontal figure and the intermediate flat or plane portion of which corresponds to the flat or plane portion of said horizontal figure.

30 The shape or figure constituting my design comprises a tongue-shaped horizontal portion A, a curved and widened portion B, forming a continuation of said portion A, the outlines of the one falling into those of 35 the other, an upright or back portion C, the curved ends of which fall over and within and correspond in outline to the curvature of the part B. The horizontally-projecting part A has a curved outline *a* at its front 40 end carried back at *a'* in substantially parallel lines, which at *b* vanish or flow into the curved outlines *b'* of the widened portion B of the shape, thus producing one harmonious and continuous outline composed of the 45 two curved lines *b'* and two substantially parallel lines *a'* and the curved line *a*. The unitary figure thus produced also has a rounded or curved smooth surface *a² b²* at its marginal edge, which vanishes into a substan-

tially plane or flat surface *a³ b³*. The upright or back portion C of the figure or shape where it springs from the flat surface *b³* of the part B has at each end a curved outline *c*, which corresponds in general contour to the curved outlines *b'* of the widened curved part B. 55 The curved surface *c' c'* at each end of this upright or back portion C continues or vanishes into the smooth plane surface *c²* of the part C at substantially the same point or relative position *b⁴* where the rounded or 60 curved surface *b²* vanishes or falls into the plane surface *b³* of the part B, and the upright curved surface *c'* of the part C also springs from the part B at the point or place where the curved or rounded surface *b²* of the part 65 B vanishes or falls into the plane surface *b³* of said part B, thus producing a general symmetrical and harmonious effect and appearance. The upright back portion C has a top D, having curved outlines *d d* at its ends and 70 straight outline *d'* at its middle portion corresponding to the outlines *c c c³* of said part C, but projecting somewhat beyond, as is clearly indicated in the drawing. The top D has at its marginal edge a curved and round- 75 ed smooth surface *d²* vanishing into a plane smooth surface *d³*, corresponding to the curved surface *b²* and plane surfaces *b³* of said part B. Within and above the tongue-shaped horizontal figure A is a similar tongue-shaped 80 horizontal figure F, having a curved outline *f* at its end, which vanishes into substantially parallel lines *f' f'*, and the marginal edge of which has a curved surface *f²*, which vanishes into a substantially plane surface *f³*, 85 the outline corresponding generally to the figure or outline of the part A. The figure F has a straight marginal line *f⁴*, which corresponds and extends parallel with the marginal base-line *c⁴* of the part C. 90

What I claim is—

The design for a water-closet seat and back, herein shown and described.

HENRY H. SIEVERT.
